UNITED STATES PATENT OFFICE.

WILLIAM H. GRANT, OF MILWAUKEE, WISCONSIN.

CARRIAGE FOR POLISHING MACHINES.

Application filed December 8, 1924. Serial No. 754,633.

This invention relates to improvements in carriages for polishing machines, more particularly for use with polishing machines for automobile bumper bars and the like.

5 It is one of the objects of the present invention to provide a carriage of the class described arranged so that its level may be varied by pressure on one edge to automatically compensate for irregularities on the 10 surface of the bumper bar carried thereon, or unevenness of the polishing wheel acting on the bar, whereby the entire surface of the bar will be evenly and uniformly polished.

15 A further object of the invention is to provide a carriage of the class described having its frame seated on springs in order that the entire surface of a bar carried by the carriage will be urged into contact with a 20 polishing wheel.

A further object of the invention is to provide a carriage for polishing machines shaped and adapted to carry bumper bars, the bars being easily and quickly positioned 25 thereon and removed therefrom.

30 A further object of the invention is to provide a wheeled carriage for polishing machines, the carriage being adapted for longitudinal travel beneath the grinding or polishing wheels of a polishing machine.

35 A further object of the invention is to provide a carriage of the class described which is of very simple construction, is strong and durable, is efficient in operation, and is well adapted for the purpose described.

40 With the above and other objects in view the invention consists of the improved carriage for polishing machines and its parts and combinations as set forth in the claims, and all equivalents thereof.

45 In the accompanying drawing in which the same reference characters indicate the same parts in all of the views:

Fig. 1 is a fragmentary side view of the carriage;

Fig. 2 is a cross-sectional view thereof; and

Fig. 3 is a fragmentary plan view thereof.

50 Referring now more particularly to the drawing it will be seen that the numeral 5 indicates the frame of the carriage, the same being formed of an elongated U-shaped metallic bar having its end portions (not shown) bent to suit the particular shape of

the bumper which it is adapted to carry. Intermediate the ends of the frame, supporting blocks 6 are fitted therewith and the frame is held to said blocks by rivets or bolts 7. The lower face of each block has 60 secured thereto a plate 8, the plates being of greater width than the blocks and projecting outwardly from the sides thereof in the form of flanges 9 and each flanged portion is formed with a pair of slots 10. 65

An axle 11 is mounted below each block transversely to the frame and the block and the frame are connected thereto by means of a pin 12 depending from the plate 8 and passing through an aperture 13 in the axle. 70 Pairs of coiled springs 14, seated in the recesses 15 in the axles, and on each side of the pins 12 and connected to the plates 8, urge the blocks and frame upwardly from the axles and support the same thereabove. 75 Transverse pins 16 in the lower ends of the pins 12 and collars 17 thererounding prevent withdrawal of the depending members 12 from the apertures 13. Upstanding studs 18 are formed on the axles on each side of 80 the apertures 13 and engage the flange slots 10. The engagement of said studs with the edges of said slots prevents the carriage frame swaying and from moving laterally or longitudinally on the springs 14, but the 85 arrangement permits depression of one side of the carriage frame if there is undue pressure thereon.

The ends of the axles 11 are reduced, as at 19, to form hubs and wheels 20 are mounted thereon and are held in place by cotter pins 21. 90

In use, the carriage is adapted to receive an automobile bumper bar or the like to be polished, and the bar is slipped over the 95 frame and held thereon by any convenient means, the surface of the bar to be polished being uppermost. The particular type of carriage here described is intended for use with polishing machines comprising a plurality of aligned units, each unit including a revolving polishing wheel, and the carriage is caused to travel longitudinally and below the wheels, so that the wheels revolve on and polish the bumper carried by the carriage. Obviously, the spring seating for the blocks 6 causes the bumper to be urged into contact with and held against the wheels. Should there be an unevenness in the bumper surface or in a polishing wheel, the 110

springs permit a depression of one side of the carriage frame to compensate for the irregularities which may occur, with the result that a smooth, even polish on a bar 5 will be obtained.

From the foregoing description it will be seen that the improved carriage for polishing machines is of very simple and novel construction, and is well adapted for the 10 purpose set forth.

What I claim as my invention is:

1. A device of the class described, comprising a pair of spaced-apart axles having wheels mounted thereon, a frame carried by said axles, springs connected to said axles and to said frame for supporting the frame above said axles, and means formed on said axles and said frame to prevent longitudinal and side movement of the frame 20 with respect to the axles.

2. A device of the class described, comprising a pair of spaced-apart axles having wheels mounted thereon, a frame carried by said axles, springs connected to said axles and to said frame for supporting the frame above said axles, and pin and slot means formed in and on said axles and said frame permitting only vertical movement of the frame with respect to the axles. 25

3. A carriage of the character described, comprising a pair of spaced-apart axles formed with recesses therein, wheels being mounted on said axles, a frame mounted above said axles, springs seated in said recesses and connected to the frame for supporting the frame above the axles, and guard 30

means on and in the frame and axles to prevent rocking or tilting of the frame.

4. A carriage of the character described, comprising a pair of spaced-apart axles 40 formed with transverse bores and top recesses on each side of the bores, wheels carried by said axles, a frame mounted above the axles and having depending pins entering the axle bores, springs seated in said axle recesses and connected to the frame for yieldingly supporting the frame above the axles, and guard means on and in the frame and axles to prevent rocking or tilting 45 of the frame.

5. A carriage for polishing machines, comprising a pair of spaced-apart axles formed with transverse bores and top recesses on each side of the bores, wheels carried by said axles, a block mounted above each axle, an elongated frame of U-shape 50 in cross-section supported by said blocks above the axles and transversely thereto, said blocks being fitted into the frame, plates connected to the bottoms of said blocks and having side flanges formed with slots therein, a pin depending from each plate and entering the axle bores, springs seated in said axle recesses and connected to the plates for yieldingly supporting the blocks and 55 frame above the axles, and pins projecting upwardly from said axles and engaging the slots in the side flanges of said plates.

In testimony whereof, I affix my signature.

WILLIAM H. GRANT.
